Attorney

UNITED STATES PATENT OFFICE.

MARIUS LATOUR, OF PARIS, FRANCE.

GENERATOR OF SUSTAINED ELECTRIC WAVES OR OSCILLATIONS.

1,354,312.

Specification of Letters Patent. Patented Sept. 28, 1920.

Application filed November 25, 1916. Serial No. 133,391.

To all whom it may concern:

Be it known that I, MARIUS LATOUR, a citizen of the Republic of France, residing at 10 Rue Auber, Paris, in the Republic of France, have invented certain new and useful Improvements in Generators of Sustained Electric Waves or Oscillations, of which the following is a specification.

This invention relates to generators of sustained waves of very low intensity for use in the receiving apparatus of the heterodyne or beat system of wireless telegraphy.

Although the principle of this system has been indicated some time ago, it has only been possible to carry it into practice when it has been found possible to produce undamped oscillations with a local generator occupying only a small space and of irreproachable regularity of working.

Meissner suggested such a generator by employing a suitable connection and a lamp with three electrodes such as "the audion" of de Forest.

A primary object of this invention is to provide a small local generator of low power undamped waves for the purpose referred to, equivalent as regards simplicity in its construction and in its setting to work to the Meissner generator. To this end I employ the metal-vapor tube with incandescent filament in combination with an oscillating circuit. The invention has no object in view except that of applying this little local generator to the generation of low-power undamped waves.

The new device operates well in practice for the very low intensities of oscillation that are required in the heterodyne system, and provides a solution of the difficulty of obtaining undamped oscillations of all frequencies with the necessary stability. It is to be observed that these oscillations are obtained without there being an arc from the anode to the cathode, and that this working must not be compared with that of a Hewitt or Wehnelt arc.

The accompanying drawings illustrate embodiments of the invention. In these drawings:

Figure 1 shows the embodiment wherein metallic mercury serves as the vapor emitting metal and as the anode, and

Fig. 2 shows the embodiment wherein the vapor emitting metal is arranged within the

bulb but a separate metal plate serves as the 55 anode.

The invention will be described with reference to the accompanying drawings but it is not limited to the precise arrangement described and illustrated.

Referring to the drawings the apparatus comprises a bulb 1 exhausted of air containing filament 2 made incandescent by means, as, for example, a source of current 3.

In the embodiment shown in Fig. 1 there is placed inside and at the bottom of the bulb 1 a small body of mercury 4.

The filament 2 when incandescent acts as a cathode and the body of mercury 4 serves as an anode, the voltage of a source of current 5 being applied between the two electrodes 2 and 4, with the interposition of an impedance 6 which may be a resistance or inductance or a combination of both resistance and inductance.

It has been experimentally verified that the characteristics of the discharge in the mercury vapor are, under these conditions, those of the arc, viz: that the voltage between the cathode and anode diminishes when the current increases, that is to say, the apparatus behaves like a negative resistance.

Sustained waves may therefore be obtained in branched circuit, comprising an inductance 7 and a capacity 8, as shown in the drawing.

Experience confirms the existence of these sustained waves for the most varied frequencies.

Instead of a body 4 of mercury the same results may be obtained by arranging in the bulb either a small amount of amalgam or metals emitting vapors for example calcium. In Fig. 2, 9 indicates this amalgam or other vapor emitting metal. It is necessary in this case to add to the generator an anode 41 having a function analogous to that of the plate in cathode generators of known type.

An important question in these mercury vapor lamps is to insure the constancy of the characteristics of the discharge. For this purpose, any suitable form may be given to the bulb and to the electrodes, and the bulb may furthermore be heated externally, for the purpose of keeping all the vol-

ume in which the discharge takes place at a constant temperature.

What I claim and desire to secure by Letters Patent of the United States is:—

- 5 1. A generator of sustained waves of very low intensity for receiving in the heterodyne system of wireless telegraphy, comprising a vacuumized bulb, a vapor emitting metal within the bulb, anode and cathode wires 10 passing into the bulb, a filament connecting the cathode wires within the bulb and a source of current connecting these wires without the bulb, and a source of continuous current and an oscillating circuit each connected between said anode and cathode wires.
- 15 2. A generator of sustained waves of very low intensity for receiving in the heterodyne system of wireless telegraphy, comprising a vacuumized bulb, metallic mercury within 20 the bulb, anode and cathode wires passing into the bulb, a filament connecting the cathode wires within the bulb and a source of current connecting these wires without the bulb, and a source of continuous current 25 and an oscillating circuit each connected between said anode and cathode wires.
- 25 3. A generator of sustained waves of very low intensity for receiving in the heterodyne

system of wireless telegraphy, comprising a vacuumized bulb, mercury amalgam within 30 the bulb, anode and cathode wires passing into the bulb, a filament connecting the cathode wires within the bulb and a source of current connecting these wires without the bulb, and a source of continuous current 35 and an oscillating circuit each connected between said anode and cathode wires.

4. A generator of sustained waves of very low intensity for receiving in the heterodyne system of wireless telegraphy, comprising a 40 vacuumized bulb, metallic mercury within the bulb, anode and cathode wires passing into the bulb, the anode wire also entering the mercury in the bulb, a filament connecting the cathode wires within the bulb and a source of current connecting these wires without the bulb, and a source of continuous current and an oscillating circuit each connected between said anode and cathode wires.

In testimony whereof I affix my signature 50 in presence of two witnesses.

MARIUS LATOUR.
